UNITED STATES PATENT OFFICE

2,435,482

PANTS DRYER AND SHAPER

Oliver S. Vigerust and Julian Layne,
La Tuna, Tex.

Application September 5, 1946, Serial No. 694,924

11 Claims. (Cl. 223—73)

1

This invention relates to a machine for use in drying and shaping trousers after laundering or cleaning thereof and is especially adapted to provide a means on which pants or trousers may be applied immediately after cleaning and laundering for supporting the trousers on a stretcher form while being subjected to a drying operation for shaping and stretching the trousers as they are dried back to their original shape and size and for removing all wrinkles therefrom and for creasing the trousers so that they will be immediately ready for pressing.

Another object of the invention is to provide a stretching and drying machine which will eliminate the use of tumbling mechanisms generally employed for drying trousers after washing to thereby eliminate the wear incident to such drying operations.

More particularly, it is an object of the invention to provide a driven conveyor means for a plurality of pants stretchers for supporting a plurality of pairs of pants or trousers in a stretched condition while the trousers are conveyed through a heated drying chamber.

Another object of the invention is to provide a novel construction of stretcher frame to operate in conjunction with a novel type of conveyor whereby the frame parts will be retracted passing over certain portions of the conveyor to allow pairs of trousers to be applied to or removed therefrom and will thereafter be expanded for stretching the trousers during the movement of the frame through the drying chamber.

Still another object of the invention is to provide a stretcher frame for trousers by means of which the trousers are resiliently held and stretched thereon and which functions to prevent the trousers from being stretched excessively so as to rupture the seams or otherwise damage the garment.

Various other objects and advantages of the invention will hereinafter become more fully apparent from the following description of the drawings, illustrating a preferred embodiment thereof, and wherein:

Figure 1 is a schematic side elevational view, partly broken away, of one embodiment of the pants stretcher and dryer;

Figure 2 is a schematic sectional view taken substantially along a plane as indicated by the line 2—2 of Figure 1;

Figure 3 is a schematic view in end elevation looking toward the left-hand end of Figure 1;

Figure 4 is a schematic side elevational view

2

of another embodiment of the invention for use in drying a single pair of trousers;

Figure 5 is a schematic horizontal sectional view thereof taken substantially along a plane as indicated by the line 5—5 of Figure 4;

Figure 6 is a transverse vertical sectional view taken substantially along a plane as indicated by the line 6—6 of Figure 5;

Figure 7 is an enlarged side elevational view 10 of a portion of the endless conveyor and showing one of the pants stretchers disposed thereon and in a retracted position;

Figure 8 is a similar view of another portion of the endless conveyor and showing one of the 15 stretcher frames in an extended position thereon;

Figure 9 is an end elevational view, partly in cross section of one of the stretcher frames, in a retracted position and disposed on the endless conveyor;

Figure 10 is a vertical transverse sectional view 20 taken substantially along a plane as indicated by the line 10—10 of Figure 8;

Figure 11 is an enlarged transverse vertical 25 sectional view taken substantially along a plane as indicated by the line 11—11 of Figure 7; and

Figure 12 is a fragmentary top plan view of a portion of the endless conveyor.

Referring more specifically to the drawings and with particular reference to Figures 1 to 3 and 7 to 12, inclusive, the numeral 15 designates generally a drying chamber which may be of any suitable construction and which is preferably of elongated rectangular shape and provided at one side thereof and adjacent the ends of the chamber 15, with door openings 16 adapted to be normally closed by sliding doors 17 which are supported by rollers attached thereto and which ride on a rail disposed above said doors. The rollers and their attaching structure are designated 18 and the overhead supporting rail engaged thereby, is indicated at 19 in Figures 1 and 3. As seen in Figures 1 and 3, a flexible member 20 is connected at its ends to the remote ends of the doors 17 and has portions trained over four or more pulleys 21, journaled on the side of the chamber 15 containing the openings 16, and other portions thereof passing over pulleys 22 which are journaled on the left-hand end 23 of the chamber 15, as seen in Figure 3. A lever 24 is pivotally mounted at its upper end at 25 on the end wall 23 and is connected to the flexible member 20 adjacent its opposite end. As seen in Figure 1, the adjacent ends of the doors 17 are connected by a flexible member 26. Accordingly,

when the lever 24 is swung to the left, as seen

in Figure 3, the doors 17 will be simultaneously moved to closed positions and when the lever is swung in the opposite direction to the right and back to its position of Figure 3 the doors 17 will be simultaneously returned to open positions.

An endless conveyor and track combination designated generally 27, extends in a zig-zag course through the chamber 15a defined by the interior of the chamber 15 and has a portion thereof extending across the front wall 15b of the chamber 15 and with adjacent portions thereto extending through the door openings 16, as clearly illustrated in Figure 2. As illustrated in Figures 7, 8, 9 and 12, the endless conveyor and trackage 27 includes a frame, designated generally 28, comprising a base 29, upright inner and outer sides 30 and 31 and cross braces 32. The base 29 and sides 30 and 31 are each formed of a plurality of angle irons which are connected together in any suitable manner at their meeting points by suitable fastenings 33 or said meeting points may be welded or otherwise secured together. The base 29 includes both longitudinally and transversely disposed angle irons 34 and 35 and the upright sides 30 and 31 likewise each include perpendicular angle irons 36 and longitudinally disposed angle irons 37. The longitudinally disposed angle irons 37 are each provided, at longitudinally spaced intervals, with inwardly projecting supporting arms 38 which are suitably secured to tubes or rods 39 which are disposed longitudinally of the conveyor frame 28 and slightly above and substantially parallel to the longitudinal angle members 37. As best seen in Figure 9, the tubes or rods 39 are supported by the arms 38 in inwardly spaced relationship to the members 37.

Each of the horizontal brace members 32 rotatably supports a sprocket wheel 40 or 41 which is journaled in a horizontal plane thereabove. The sprocket wheels 40 are located in the portion of the conveyor frame disposed on the outer side of the wall 29 and intermediate of the ends thereof, and the remainder of the sprocket wheels 41 are disposed at the ends of the conveyor frame which is disposed externally of the wall 29 and around the portion thereof contained within the chamber 28. An endless sprocket chain 50 is trained over the sprocket wheels 40 and 41, as best illustrated in Figure 2, so as to follow the undulating, endless path of the frame 28. As best illustrated in Figures 7, 9 and 12, the two sprocket wheels 40 are provided with crown type worm gears 42 on the upper sides thereof. A shaft 43 is journaled within and longitudinally of the exposed part of the frame 28 and above the sprocket wheels 40 by means of brackets 44, containing bearing portions, which are secured to the uprights 36 of the side 30. The shaft 43 is provided with a pair of worms 44 which are keyed thereto and each of which is disposed to mesh with one of the worm gears 42.

As best seen in Figures 9 and 12, a suitable source of power such as an electric motor 46 is secured to the base 29 and is provided with a driven belt pulley 47 which is disposed in transverse alignment with a belt pulley 48 on the shaft 43. An endless belt 49 is trained over the belt pulleys 47 and 48 for revolving the shaft 43 and the worms 44 to revolve the sprocket wheels 40 in a counter-clockwise direction, as seen in Figures 2 and 12, for moving the endless sprocket chain and the idler sprocket wheels 41 in the same direction as the driven sprocket wheels 40.

A plurality of carriages, each designated gen-

erally 51, is movably supported on the conveyor frame 28 and disposed for movement therealong. Each of the carriages 51 includes an elongated, substantially rectangular frame, designated generally 52, which is formed of angle members and which includes an open rectangular upper frame section 53, a lower, open rectangular frame section 54 and upright corner posts 55 connecting the frame sections 53 and 54 at their corners. The bottom frame section 54 is provided with four or more depending, outgoing opening channel shaped hangers 56 in each of which is journaled a pair of grooved rollers 57 which are disposed in vertically spaced relationship and which are adapted to engage above and beneath the rails 39 which are of circular cross section and substantially conforming to the curvature of the grooves of the rollers 57 for movably mounting the carriage 51 thereon. As clearly illustrated in Figures 8 and 9, a plurality of pairs of rollers 57 of each carriage 51 engage each of the rails 39.

As best seen in Figures 9 and 10, the upper frame section 53 is provided with a pair of longitudinally disposed rails 58 which are likewise circular in cross section and which extend from end-to-end thereof and which are secured to the end portions of the frame section 53 and disposed in inwardly spaced relationship to the sides thereof and which engage pairs of grooved rollers 59, corresponding to the rollers 57 and which are mounted in channel shaped hangers 60 of the same construction as the hangers 56.

The hangers 60 are secured to and depend from the corresponding arcuate waist band sections 61 which form the lower end of a pants stretching frame, designated generally 62, and each of said sections 61 is provided with a plurality of hangers 60 at each side thereof. The stretcher frame 62 also includes arcuate seat engaging sections 63 which are larger than and disposed above the section 61 and supported thereby by means of upwardly and outwardly extending brace members 64. The parts 61, 63 and 64 may be formed of any suitable, substantially rigid metal. As best seen in Figure 10, the band sections 61 and 63 are provided with diametrical connecting portions 65 and 66, respectively, which extend between the ends of the arcuate portions of said bands and which are provided with intermediate, outwardly off-set portions 67 and 68, for a purpose which will hereinafter become apparent. The band sections 61 are each provided with two upwardly projecting apertured ears 69, disposed adjacent the ends of the arcuate portions thereof and to each of which is pivotally connected an upwardly extending brace 70. The upper ends of the braces 70 are each secured rigidly to the lower end of an upwardly extending stretcher arm 71, so that each of the band sections 61 supports a pair of pivotally mounted stretcher arms 71. As best seen in Figure 9, the upper, free ends of the stretcher arms 71, which constitute a pair of said arms and are supported by the same band section 61, are connected by an inverted U-shaped member 72, which is preferably in the form of a strand of relatively heavy, resilient wire.

A supporting standard 73 extends upwardly from each of the band sections 63 and is rigidly connected thereto, intermediate the ends of the arcuate portion thereof. The standards 73 converge toward their upper, free ends and are provided with longitudinally spaced inwardly projecting supporting arms 74 which support bearings 75, disposed on the inner ends thereof. A

rod 76 is reciprocally mounted in the bearings 75 of each of the standards 73. Each rod 76 has a collar 77 secured thereto above its upper bearing 75 and to which the adjacent ends of a pair of links 78 are pivotally connected. The stretcher arms 71 are provided adjacent their upper ends with a series of longitudinally spaced apertures 79 to selectively receive fastenings 80, by means of which the remote ends of the links 78 are pivotally connected to the stretcher arms 71. A rod 81 is reciprocally mounted in a bearing portion of a bar 82 which is secured to and disposed transversely of the lower section 54 of the carriage 51. The rod 81 is disposed for reciprocation in substantially a vertical plane and is provided at its upper end with a cross head 83 to which the adjacent ends of a pair of rigid links 84 are pivotally connected. As seen in Figure 8, the remote ends of the links 84 are pivotally connected to ears 85 which project from the waist band portions 61. The links 84, near their adjacent ends, are provided with upwardly projecting apertured ears 86 to which is connected a pair of rigid links 87. The opposite ends of the links 87 are pivotally connected at 88 to the lower ends of the rods 76. The rod 81 is reciprocally disposed in a sleeve 89 which is located beneath the carriage 51 and which is provided with brace arms 90 which extend therefrom and which are secured to the underside of the carriage 51 and with additional connecting arms 91 which project therefrom and which are secured to the upper side of the chain 50, as best seen in Figure 8. The rod 81 is provided adjacent its upper end with a fixed collar 92 and carries a contractile coiled spring 93 thereon and between the collar 92 and the bearing of the bar 82; said spring being connected at 94 to the collar 92 and at 95 to the bar 82.

As best illustrated in Figure 1, the portion of the frame 28 which is located on the outer side of the wall 15b is provided with a longitudinally extending track 96 including an elevated, substantially horizontal intermediate portion 97 and downwardly inclined end portions 98 forming ramps. As seen in Figure 8, the rod 81 is provided with a depending fork 99 at its lower end in which a roller 100 is journaled. The roller 100 is disposed to ride over the track 96 as its carriage 51 moves along the portion of the endless conveyor and track 27 which is located on the outer side of the chamber 15 for initially forcing the rod 81 upwardly, for maintaining the rod in an elevated position for a predetermined distance of travel of the carriage 51, and for thereafter permitting the rod to be drawn downwardly by the recoil action of its spring 93, as the roller 100 rides down one of the ramps 98. As seen in Figure 2, the drying chamber 15a is provided with steam coils located adjacent the bottom or floor thereof and beneath the frame 28 of the endless conveyor 27. The roof of the structure 15 is provided with openings 102 in which driven exhaust fans 103 are disposed for exhausting air from the chamber 15a through the openings 102, above each of which is disposed a cap or cover 104.

From the foregoing it will be readily obvious that a plurality of carriages 51, each supporting a stretcher frame 62, may be mounted on the rails 39 and connected to the chain 50 by the arms 81 to be moved by the endless undulating route of the endless conveyor across the front wall 15b and back and forth through the chamber 15a. The carriages 51 are preferably so arranged that a plurality of carriages and stretch-

er frames 62 is at all times disposed within the chamber 15a so that as one carriage enters the chamber another carriage will move outwardly therefrom. Assuming that the chain 50 is moving in a clockwise direction, as seen in Figure 2, and that a pair of trousers has been removed from stretcher frame 62 and another pair of trousers to be dried and stretched has been applied thereto while said frame was over the horizontal portion 97 of the track 96, as said carriage 51 and stretcher frame 62, only one of which has been illustrated, moves toward the left and toward the left-hand door or opening 16, another stretcher frame and carriage is approaching the other door opening 16. By moving the lever 24 in a counter-clockwise direction, as seen in Figure 3, to its position of Figure 3, the two doors 17 will be opened as seen in Figure 1 so that as the one carriage and stretcher frame enters the chamber 15a through the left-hand door opening 16 another carriage and stretcher frame will pass outwardly through the other, right-hand door opening 16. As the last mentioned carriage and stretcher frame begins to traverse the straight portion of trackage 28, which is disposed outwardly of the wall 15b, its roller 100 will engage the ramp 98, located therebeneath, to force the rod 81 upwardly, so that when the carriage frame has reached the position over the horizontal track portion 97 the parts will be in the position illustrated in Figure 7 and with the rods 76 elevated so that the stretcher arms 71 are contracted. Likewise, the links 84 will be drawn upwardly so that the band sections 61 and 63 will have been drawn toward one another and into their positions of Figure 7, from their positions of Figure 8, with said parts riding on the rails 58 of the carriage 51 through engagement of the rollers 59 therewith. With the stretcher frame 62 thus contracted, the pair of trousers which have been dried can be readily removed from the frame 62 and another pair of trousers applied thereto, during the time that the carriage frame is traversing the horizontal track portion 97. In applying the trousers to the frame 62, the waist band of the trousers is engaged about the band sections 61 and the seat or hip portion thereof is fitted around the band sections 63. Each of the legs of the trousers engages a pair of the stretcher arms 71 and is disposed over the uprights 73, which is located outwardly thereof. As a result, as the carriage frame continues to move along the endless conveyor and track, the roller 100 will engage the other ramp 98 and ride downwardly therealong to permit the spring 93 to retract the rod 81 and the parts connected thereto in a downward direction. This will force the band sections 61 and 63 outwardly of one another, through engagement of the rollers 59 with the rails 58, and will also draw the rods 76 downwardly so that their links 78 will swing the stretcher arms 71 outwardly for stretching the pants legs and other portions of the trousers. This operation is repeated with each carriage and stretcher frame as it moves over the track 96. During the movement of the carriages and stretcher frames through the drying chamber 15a, the hot air from the steam coils 101 is drawn upwardly by the fans 103, through the stretcher frame 62 and the trousers contained thereon, not shown, and the moist air is exhausted through the outlets 102, so that the trousers are dried and stretched back to their natural shape and size during their passage through the drying chamber 15a.

By means of this operation, a pair of trousers immediately after washing or cleaning and without being subjected to a tumbling operation for extracting the water or liquid therefrom, may be applied to one of the stretcher frames 62 and air dried while making one circuit of the conveyor 27 and while being dried will be resiliently held in a stretched condition to prevent shrinkage thereof. It will be noted that the frame 62 is resiliently held in extended position by the spring 93 so that the stretching pressure applied to the garment is of a yieldable type to prevent an undue stretching pressure being exerted thereon which would tend to damage the cloth or seams thereof and also to adapt the stretching frames to trousers of various sizes.

The stretching and drying apparatus as previously described is adapted for use in large plants having a large number of pairs of trousers which are washed or cleaned daily. For smaller plants, a slightly modified form of the unit may be provided and which is illustrated in Figures 4, 5 and 6. In this embodiment of the invention, a relatively small drying chamber 105 is provided having door openings 106 in opposite sides thereof and which are normally closed by doors 107. The doors 107 are slidably mounted on guide-ways 108, disposed on the outer side of the building 105 and adapted to be manually actuated independently for movement to open or closed positions. The structure 105 contains a steam coil 109 which is located adjacent the bottom or floor thereof and is provided with a single exhaust fan, not shown, disposed in an opening of the roof of the structure 105 and contained within an apertured hood or cap 110. The exhaust fan and roof opening may correspond with the exhaust fan 103 and roof opening 102 as previously described and as illustrated in Figure 1, for carrying off hot air from the steam coil 109. As disclosed in Figures 4, 5 and 6, a substantially straight section of track 111 is provided having elevated, spaced parallel rails 112, corresponding to the rails 39 and for supporting a carriage 51, of the same construction as the carriage previously described and on which is mounted a stretcher frame 62 corresponding to the stretcher frame previously described. The track 111 is not provided with conveyor means and in lieu of the track member 96 is provided at each end thereof with a center rail 112, having a downwardly inclined inner end or ramp 113. The track section 111 extends through the drying chamber 105 and through each of the openings 106 thereof. When the carriage and frame is located at either end of the track 111, the roller 100 thereof will be in engagement with the horizontal portion of the rail 113 for retracting the stretcher frame 62, as previously described, so that trousers thereon can be removed and another pair, to be dried and stretched, can be applied thereto. The carriage and frame is then moved toward the drying chamber 105 and the adjacent door 107 is opened to permit the carriage and frame to enter through the door opening 106, after which the door is closed and the frame left in the chamber for a sufficient time to permit the trousers thereon to be dried. As the carriage 51 moves toward the door opening 106 its roller 100 will ride over the ramp 114 to permit the spring 93 to expand the frame 62, as previously described. After the drying operation has been completed, the other door 107 is opened and the carriage and frame is manually drawn from the drying chamber 105 to the opposite end

of the track 111, and in approaching said end the roller 100 will engage the other ramp 114 and ride up onto the other horizontal rail portion 113, to again retract the frame 62 so that the dried and stretched trousers can be removed therefrom and another pair of trousers, to be dried and stretched, is then applied and this operation is repeated by moving the carriage and frame in the opposite direction on the track 111.

10 Various other modifications and changes are likewise contemplated and may obviously be resorted to, without departing from the spirit and scope of the invention as hereinafter defined by the appended claims.

15 We claim:

1. In an apparatus for stretching and drying trousers, a drying chamber having means for circulating hot air therethrough, a track extending through said drying chamber and being provided 20 with a plurality of rails, a carriage having wheels for engaging said rails, a pants stretching frame mounted on said carriage and provided with spring means for normally retaining the frame in an extended position for stretching a pair of 25 trousers disposed thereon, and means forming a part of the track and disposed in a section thereof for engaging a portion of the stretcher frame for retracting the frame for permitting a pair of trousers to be removed therefrom or applied thereto, said carriage and its supporting frame being mounted for movement on the rails for movement through the drying chamber.

2. A drying unit as in claim 1, and driven conveyor means associated with the track frame and 30 connected to the carriage for conveying the carriage through the drying chamber.

3. A drying unit as in claim 1, said track frame being endless and being provided with a portion 35 disposed within the drying chamber and a portion disposed externally thereof, said first mentioned portion being of undulating formation.

4. A drying unit as in claim 1, said track frame being endless and being provided with a portion 45 disposed within the drying chamber and a portion disposed externally thereof, said first mentioned portion being of undulating formation, and driven conveyor means associated with the track frame and connected to the carriage for conveying 50 the carriage through the drying chamber.

5. A drying unit as in claim 1, said drying frame being formed of complementary sections movable on said carriage toward and away from one another, and each of said drying frame sections being extensible laterally in a direction substantially at right angles to the direction of movement of the sections, relatively to each other.

6. A drying unit as in claim 1, and driven conveyor means associated with the track frame and 60 connected to the carriage for conveying the carriage through the drying chamber, said endless conveyor means including an endless chain, sprockets journaled in the track frame and over which the chain is trained, certain of said sprockets having crown type worm gears, a driven shaft journaled in a portion of the track frame, and worms keyed to said shaft and meshing with said worm gears for driving said chain.

7. In a stretching frame for trousers, a pair of 65 frame sections, a base, wheeled means for mounting the frame sections for movement toward and away from one another on said base, each of said frame sections having arcuate waist and seat engaging portions and a trousers leg engaging portion, link and push rod means slidably mounted

75

in the stretcher frame and base and movable in one direction for moving the frame sections away from one another and for expanding the trousers leg engaging portions of each of the frame sections, and spring means for normally urging the push rod and link means in said direction and yieldably holding the parts in extended positions.

8. A device as in claim 7, a track provided with rails, wheel means mounted on said base and engaging said rails for mounting the stretcher frame for movement along said track, and means forming a part of the track frame for engaging a portion of the push rod and link means for moving said parts in the opposite direction to retract the stretcher frame parts.

9. A device as in claim 7, a track provided with rails, wheel means mounted on said base and engaging said rails for mounting the stretcher frame for movement along said track, and means forming a part of the track frame for engaging a portion of the push rod and link means for moving said parts in the opposite direction to retract the stretcher frame parts, and a drying chamber through which said track frame extends and on which the stretcher frame is movable thereon for drying and stretching a pair of trousers supported on the frame, while the frame is passing through the drying chamber.

10. In a drying unit for trousers, a drying

chamber, a track extending therethrough, an expansible drying frame mounted for movement on said track and adapted to support a pair of trousers to be dried, and yieldable means for holding the frame in an extended position for stretching the trousers disposed thereon and while the frame is moving through the drying chamber.

11. A drying unit as in claim 10, said resilient means for extending the stretcher frame including a push rod having a depending end extending into the track frame, and means forming a part of said track frame and disposed externally of the drying chamber for engaging and retracting the push rod for retracting the stretcher frame to facilitate the removal from or the application of a pair of trousers thereto.
